UNITED STATES PATENT OFFICE

152,371

DESIGN FOR A DISPLAY FIXTURE

Howard M. Schick, Lee's Summit, Mo.

Application April 28, 1947, Serial No. 138,653

Term of patent 14 years

(Cl. D80—11)

To all whom it may concern:

Be it known that I, Howard M. Schick, a citizen of the United States, residing at Lee's Summit, in the county of Jackson and State of Missouri, have invented a new, original, and ornamental Design for Display Fixture, of which the following is the specification, reference being had to the accompanying drawing, forming part thereof.

The figure is a perspective view of a display fixture showing my new design, the opposite side and end of said fixture being substantially similar to the side and end shown.

I claim:

The ornamental design for a display fixture, substantially as shown and described.

HOWARD M. SCHICK.
